UNITED STATES PATENT OFFICE.

RALPH J. WELLS, OF DAYTON, OHIO.

RAILWAY-TIE.

1,218,141.

Specification of Letters Patent.

Patented Mar. 6, 1917.

Application filed May 24, 1915. Serial No. 30,096.

To all whom it may concern:

Be it known that I, RALPH J. WELLS, citizen of the United States, residing at Dayton, in the county of Montgomery and State of Ohio, have invented certain new and useful Improvements in Railway-Ties, of which the following is a specification.

My invention relates to railway track structures and more particularly to a new 10 and novel form of cross tie therefor.

The object of the invention is to simplify the structure of such devices whereby they will not only be cheapened in construction, but will be more efficient in use, of maximum 15 strength, safe in operation, and unlikely to get out of repair.

A further object of the invention is to provide a form of sleeper or support for the railway rail which will afford a degree 20 of resiliency simulating that of the earth bedded wooden tie formerly used while possessing the permanency of modern concrete constructions.

A further object of the invention is to provide a tie construction which is easily capable 25 of transportation and readily adaptable to different conditions of use and which may be readily and quickly assembled into the track construction, and in which the perishable parts including the fastenings, the sleeper block and cushion may be conveniently and quickly replaced.

With the above primary and other incidental objects in view, as will more fully 35 appear in the specification, the invention consists of the features of construction, the parts and combinations thereof, and the mode of operation, or their equivalents, as hereinafter described and set forth in the 40 claims.

Referring to the drawings, Figure 1 is a perspective view of the cross tie forming the subject matter hereof. Fig. 2 is a longitudinal sectional view of the tie units. Fig. 3 is 45 a transverse sectional view. Fig. 4 is a bottom plan view of one of the tie units. Fig. 5 is a top plan view of the construction forming the subject matter hereof applied to special track work. Fig. 6 is a transverse 50 sectional view of the completed track construction. Fig. 7 is a perspective view of the sleeper block removed from the track structure. Fig. 8 is a perspective view of the sleeper block divided into separable sections to facilitate replacement. 55

Like parts are indicated by similar characters of reference throughout the several views.

Among the many attempts to provide an artificial tie possessing the peculiar qualifications and resiliency of the earth bedded wood tie, numerous attempts have been made to provide ties of concrete or other similar material with an embedded wooden sleeper block. In some instances such wooden 60 sleeper blocks have been submerged in a body of asphaltum, pitch or other similar material. None of these constructions, however, have proved sufficiently successful to warrant general adoption and none have 65 gone into general use. In applying such asphalt or pitch embedded sleeper blocks to concrete ties, it has heretofore been the custom to provide a recess in the tie considerably larger than the sleeper block and 70 to entirely surround the sleeper block with yielding or resilient packing material. It 75 has been found in practice, however, that such packing material when softened by summer heat is displaced and forced out of 80 the recess or cavity by the pressure and constant pounding of traffic upon the sleeper block. Such plastic packing material cannot be retained in structures which contemplate submersion or inclosing the sleeper 85 block in plastic packing material. It has been found by experiment that such plastic cushioning material may be successfully retained by making the sleeper block a closure for the recess or receptacle and allowing 90 only sufficient clearance between the block and the walls of the recess to compensate for the expansion and contraction of the parts. This feature has been embodied in the present invention, in which the rail rests directly 95 on the sleeper block which is in turn cushioned upon the packing material. Another disadvantage of artificial ties as ordinarily constructed is that of excessive weight and the inconvenience of transporting the 100 ties from the place of manufacture to that of use. To overcome this difficulty the cross tie forming the subject matter hereof is of skeleton form capable of being shipped in knocked down or disassembled form to be 105 assembled and embedded at the place of use.

Referring to the drawings, 11 are box-like receptacles preferably of sheet metal but which may be of fiber, composition, or other suitable material. Fitted within the 110

receptacles 1 are sleeper blocks 2 of such proportion in relation with the receptacle 1 as to form a closure therefor. The sleeper blocks 2 are shaped to fit the receptacles 1 leaving sufficient clearance to compensate for expansion and contraction of the parts. Before inserting the sleeper block 2 within the receptacle 1 a cushion or bed 3 is provided therein of plastic or semi-plastic material 10 such as asphaltum, pitch, tar, rubber, composition, or other suitable yielding material. This material underlies the sleeper block 2 and forms a yielding resilient cushion 3. The clearance space 4 intermediate the block 15 and the sides of the receptacle are likewise filled with packing material. However, this clear space comprises a mere crevice too small to permit the escape of the material from beneath the block. Material of the 20 character described and consistency of that employed for the cushion will not readily pass through a restricted crevice such as that afforded by the clearance space. Therefore the sleeper block constitutes a 25 closure for the receptacle 1 which serves to retain the cushioning material therein. The block 2 preferably extends somewhat above the level of the top of the receptacle 1 and although free to move downward 30 against the tension of the cushion 3, it is limited in its upward movement by studs or bolts 5. The sides of the sleeper block 2 are recessed or notched, as at 6, to receive the studs or bolts 5. The sleeper block preferably comprises an integral unit in the 35 original construction. However, the block as well as the cushion 3 and fastening bolts 5 will require occasional replacement. At such time it is an easy matter to cut out 40 the wooden sleeper block 2. The rail may be released from the clamp plates 8 at opposite sides of the point of operation. The rail may then be jacked up to give access to the receptacle 1. To avoid the necessity 45 of elevating the rail to an extreme height sufficient to permit the insertion of the block 2 over the studs 5, the renewal block is preferably formed in sections as shown in Fig. 8. The side sections 2^a are first inserted and 50 moved outward with the notches 6 engaging the studs and the intermediate section 2^b is then inserted. To facilitate the insertion of the intermediate section 2^b this section may be again divided diagonally as 55 at 2^c. The respective portions may then be inserted from opposite sides. The track rails 7 rest directly upon the sleeper blocks 2 and are secured in position by clamping plates 8 engaging the base flanges of the 60 rails and secured by the nuts 9 upon the studs 5. In order that the fastening studs 5 may be renewed without destroying the structure, the receptacles 1 are provided with key hole slots 5^a in their bottoms in 65 which the heads of the bolts are engaged.

When the block has been removed, as before described, the studs 5 may be easily shifted laterally in the key hole slots 5^a and then disengaged therefrom, it being understood that sufficient clearance or pocket is provided in the underlying concrete to permit such movement. This may be accomplished by drilling or chipping away the concrete through the key hole slot after the block and cushion have been removed. 75

This capability for replacement has been found quite valuable as it enables the repairs to be made without interfering with the traffic over the road as would be the case if it were necessary to destroy and replace 80 the concrete body or formation. In such case traffic would necessarily be suspended until the new material might set or harden.

The receptacles 1 with the inserted cushioned sleeper block are connected one to 85 the other by means of transverse angle bars 10 preferably formed in two sections and joined intermediate the receptacles 1, as indicated at 11. These angle bars are preferably located at the base angles of the receptacles 1 and 90 are engaged therewith by the studs 5 which extend through the bottoms of the receptacles 1 and engage in recesses or notches 12 in the angle bars. The angle bars are preferably connected one with the other by 95 means of cross bars 13 riveted or bolted to the angle bars. The angle bar sections thus secured to each receptacle form parallel arms projecting laterally from the receptacle and are adapted to be engaged with similar parallel arms projecting from the opposite receptacle to form the tie. In placing the device in use parallel trenches may be excavated across the road bed in the positions to be occupied by the ties whereby independent concrete ties will be formed or the 100 road bed may be excavated throughout. In the latter case the excavation is preferably deepened by longitudinal trenches at each side beneath the positions occupied by the 105 receptacles 1. The cross tie sections are then attached to the base flanges of the rails by means of the clamping plates and studs and the angle bars are connected one to the other in proper relation. The track rails are leveled and adjusted to proper grade. The skeleton ties are thus held suspended beneath the track rails and within the excavated cross trenches or within the excavated 110 road bed. The cross trenches or road bed 115 are then filled with grouting or concrete as indicated in Fig. 6. This grouting extends around and beneath the receptacles 1 and the connecting angle bars and at its upper surface extends over the edge of the receptacle 120 1 into close proximity to the sleeper block 2, as indicated at 14. This serves to cover or close the clearance space between the block and the interior of the receptacle. It is obvious, however, that the structure described 125 130

may be embodied in independent ties manufactured at a distance from the point of use.

It is to be understood that the receptacles 1 and the embedded sleeper blocks may be 5 located at any desired points throughout the length of the angle bar. This is found especially convenient in the placing of special track work such as crossings, frogs, etc. In Fig. 5 there is shown a supplemental receptacle 15 with its sleeper block located intermediate the primary sleeper blocks supporting the track rails. This additional sleeper block is adapted to support a rail 16 inclined to the track, *i. e.*, a cross-over or sliding rail.

15 In track constructions for electric railways the construction herein described forms a cross bond or electrical connection between the rails.

It is found in practice that the construction as above described affords a structure of 20 great durability, possessing the required degree of resiliency, and which is convenient and economical to install. While the reduction of the extent of the clearance space may 25 seem but a variation and small step, it is however, the difference which has turned failure into success.

From the above description it will be apparent that there is thus provided a device of 30 the character described, possessing the particular features of advantage before enumerated as desirable but which obviously is susceptible of modification in its form, proportion, detail construction or arrangement 35 of parts without departing from the principle involved or sacrificing any of its advantages.

While in order to comply with the statute 40 the invention has been described in language more or less specific as to certain structural features, it is to be understood that the invention is not limited to any specific details but that the means and mode of operation herein described comprise but one method of 45 putting the invention into effect and the invention is therefore claimed broadly in any of its possible forms or modifications within the scope of the appended claims.

Having thus described my invention, I 50 claim:

1. In a railway tie, two independent metallic box-like receptacles spaced apart but detachably connected one with the other, a cushion body located within each of the receptacles, and a wooden sleeper block within each of the receptacles and resting on the cushion body.

2. In a device of the character described, a metallic box-like receptacle, a resilient bed 60 of asphaltum or similar material capable of assuming a semi-fluid condition within the receptacle, and a wooden sleeper block fitted within the receptacle and resting upon the said resilient bed, the proportions of the 65 block conforming to those of the receptacle

sufficiently close to form a closure to prevent the escape of the material when in a semi-fluid condition.

3. In a device of the character described, a receptacle, a yielding resilient cushion 70 therein, a sleeper block within the receptacle resting upon the resilient bed and means for limiting the outward movement of the sleeper block in relation with the receptacle while permitting the inward movement thereof independent of said limiting means against the yielding resistance of the resilient cushion.

4. In a device of the character described, a receptacle, a resilient cushion in the receptacle, a sleeper block resting upon the cushion, and studs connected with the receptacle upon which the sleeper block is free to move against the tension of the cushion, and heads upon the studs limiting the outward movement of the sleeper block.

5. In a device of the character described, a receptacle, a body of material capable of assuming a semi-fluid condition within the receptacle and a sleeper block forming a 90 closure for the receptacle to prevent the escape of the semi-fluid material from the receptacle.

6. In a railway construction, a metallic receptacle, a body of plastic material within 95 the receptacle, a wooden sleeper block conforming to the interior form of the receptacle and resting upon the body of plastic material, and a body of concrete or similar material in which the receptacle is embedded.

7. In a railway tie, two independent metallic receptacles spaced one from the other, a body of plastic material within each of the receptacles, wooden sleeper blocks located within the receptacles and resting upon the plastic material, and intermediate means detachably connecting the receptacles one to the other.

8. In a railway tie unit, a box-like receptacle, two laterally disposed parallel arms projecting from the receptacle, a wooden sleeper block within the receptacle, and a cushion body within the receptacle beneath the sleeper block, said units being 115 adapted to be arranged in pairs with the arms of one unit connected to those of the other unit.

9. In a railway tie, a main structure comprising two spaced independent containers 120 adapted to be embedded in a concrete foundation, wooden sleeper blocks seated therein, attachment bolts for the sleeper block, said main structure having key hole slots in the bottoms of the containers therein in which 125 the bolts are engaged.

10. In a railway tie, independent containers connected one to the other, a wooden sleeper block located within the container, an attachment bolt therefor, the container 130

having a key hole slot in the bottom thereof in which the bolt is detachably engaged.

11. In a railway tie, a main structure, a wooden sleeper block seated therein, said block having a groove in the face thereof and an attachment stud in the main body engaging in the said groove.

12. In a railway tie, two independent box-like housings spaced one from the other, connecting means extending from one housing to the other, a cushion located in each of the housings, and a sleeper block also located within each housing and resting upon the cushion, said housings and intermediate connection being adapted to be embedded in a body of concrete.

13. In a railway tie, a chambered main body, a sleeper block comprising a plurality

of separable sections seated in said chamber, and a cushion within the chamber common to all the sections and means for detachably engaging the sections beneath overhanging retainers.

14. In a railway tie, two separate box-like housings spaced one from the other and embedded in a concrete body, a cushion located in each of the box-like housings, a sleeper block also located in each of the housings and resting upon the said cushion, substantially as specified.

In testimony whereof I have hereunto set my hand this 22nd day of May, A. D. 1915.

RALPH J. WELLS.
